UNITED STATES PATENT OFFICE.

WILLIAM H. CURTIS, OF PORTLAND, OREGON.

FLUID-ACTUATED MEANS FOR CONTROLLING AN ENGINE.

1,217,117.

Specification of Letters Patent. Patented Feb. 20, 1917.

Application filed August 26, 1914. Serial No. 858,753.

To all whom it may concern:

Be it known that I, WILLIAM H. CURTIS, a citizen of the United States, and a resident of the city of Portland, county of Multnomah, State of Oregon, have invented a certain new and useful Improvement in Fluid-Actuated Means for Controlling an Engine, of which the following is a specification.

The direct object of my invention is to 10 operate the control lever of an engine by fluid actuated means controlled from a distant point and operating to hold said control lever in the position to which it has been moved by said actuating means. Thus 15 in a vessel the control of the engine could be placed in a pilot house, thereby giving the navigator direct control of the engine, instead of merely indirect control, through the medium of the engineer, and by signals 20 given to the latter.

Another result of my invention is, that the direct control of the engine so placed in the hands of the pilot is more efficient; it permits the pilot to instantly control 25 the speed, and to stop and reverse the engine as the circumstances may require.

Another result attained by my invention is, that the clutch mechanism will, under all circumstances, be operated gradually, and 30 cannot be thrown into action abruptly even by a careless operator. This feature is essential in marine engines, since the resistance offered to the propeller by the water is so great as to frequently cause the breaking 35 of the propeller blades, or injury to the operating means thereof, when the clutch mechanism is unskillfully handled. My invention is also serviceable to operate steering gear and any device embodying a member 40 to be moved by a mechanical actuating force and held in the position to which moved.

The details, mode of operation, and particular features of my invention will be 45 more readily understood by a description of the accompanying drawings, in which:

Figure 1 is a front elevation, showing in diagrammatic form a marine engine and the application of my invention for controlling the clutch and reverse gear from a point remote;

Fig. 1^a is a partial rear elevation corresponding with Fig. 1;

Fig. 2 is a partial left-end elevation of 55 the pneumatic piston cylinder shown in Fig. 1, and of the valve which controls the flow

of air into and out of opposite ends of said cylinder;

Fig. 3 is a right-side elevation of the parts shown in Fig. 2;

Figs. 4 to 6, inclusive, are horizontal sections of the valve mechanism, taken in numerical order, on the lines 4—4, 5—5 and 6—6 of Fig. 2, respectively;

Fig. 7 is a vertical section taken approximately on the line 7—7 of Fig. 2; and

Fig. 8 is a larger-scale rear elevation of that part of the valve gear embodying the floating link.

For convenience I have illustrated my invention as applied to the clutch and reversing gear of a marine engine of the internal combustion type; but, of course, I do not limit myself to any particular type of engine.

a represents a marine engine of the standard internal combustion type. *b* is the lever for controlling the throttle of the engine, and *c* is the lever for controlling the sparking mechanism of the engine.

d represents the clutch and reverse gear mechanism, and *e* is the operating lever thereof. *f* represents the propeller shaft and *g* the propeller blades. The control lever, *e*, of the clutch and reversing gear is detachably connected to and operated by my fluid actuated means which are operated by the lever *u'* on the stand *u*; and the levers *b*, *c*, connected to the throttle and the sparking mechanism of the engine, are operatively connected to the levers, *u²*, *u³*, also located on the stand *u*, which is assumed to be in the pilot house of the vessel.

As shown in the drawings, my fluid actuated means for operating the clutch and reversing mechanism of the engine consist of a pneumatic cylinder *h*, provided with lateral trunnions *i*, by which it is pivotally mounted in the standards *j*; and in the cylinder *h* reciprocates a piston *k*, having a piston rod *m*, on the extremity of which is a shackle *n*, by which it is connected to the extremity of the lever *e*. The shackle is provided with an elongated slot *q*, and the lever *e* is provided with an eye in its upper end, and these parts are connected by a pin *o*, which extends through the eye of the lever *e*. See Fig. 8. Pivoted latch-plates *p* hold the pin *o* in place. This arrangement facilitates the disconnection of the lever *e* from the pneumatic cylinder and piston when it is desired to control the clutch and

reversing gear manually. The shackle is made with a lateral stud n' to which is connected the link y of the valve-gear mechanism. See Figs. 1 and 8. The slot q is provided in the shackle n so that when the fluid actuated mechanism has been operated to set the clutch mechanism in its ahead position, the operating lever u' may be slightly reversely moved, and thus relieve the control lever, e , of all strain, without moving it from its ahead position, thereby preventing undue friction and wear on the internal parts of the clutch mechanism.

The pneumatic cylinder h is provided with a valve r , which is connected to the opposite ends of the cylinder by the pipe lines t, t' , and thus controls the inflow and exhaust of the actuating fluid into and from the opposite ends of the cylinder. The storage tank s is connected with the valve r through a pipe s' .

The valve r comprises a casing r' mounted on a bracket r^2 , which includes a bearing r^{2x} for the valve cam shaft r^4 , on the extreme end of which is a lever arm r^8 , the rotary movement of which is limited by stops r^3 , integral parts of the bracket r^2 . See Fig. 2. The portion of the cam shaft r^4 underlying the valve casing is provided with lateral arms r^5 , on which cams r^6 are secured by the set screws r^7 . Said cams have their working surfaces on arcs of circles centered from the axis of the shaft r^4 . A floating link r^9 is pivoted on the outer end of the arm r^8 (see Figs. 2 and 8) and the lower end of the link r^9 is pivoted to the link y , of the valve gear mechanism. The floating link r^9 is variably connected by the link r^{10} to a bell crank x , and the latter is connected by a link x' to u . The operating lever u' on the stand u . The throttle control mechanism, including the lever b , is also carried to the stand u by means of bell cranks w, w' and links w^2, w^3 , and is connected to the throttle operating lever u^2 . The spark controlling mechanism is also carried to the stand u by means of bell cranks v, v' and links v^2, v^3, v^4 , and v^5 and is connected to the operating lever u^3 .

The valve mechanism r is so constructed that when the air is admitted into one end of the cylinder h it will be simultaneously and proportionately exhausted from the opposite end of said cylinder; the construction being as follows:

The valve casing r' is made with two air inlet valve chambers r^{11}, r^{12} , and two exhaust port valve chambers r^{15}, r^{16} . Compare Figs. 4, 5, 6 and 7. The air supply pipe s' connects with the valve casing r' through a duct r^{13} , connected by passageways r^{14} with said air inlet valve chambers r^{11}, r^{12} . See Fig. 4. The exhaust port valve chambers r^{15} and r^{16} are connected by a passageway r^{17} , which opens to the atmosphere.

As shown in Figs. 5 and 7, the inlet port

valve chamber r^{11} and the exhaust port valve chamber r^{15} are connected with a passageway, t^2 , and the exhaust port valve chamber r^{16} , and the inlet port valve chamber r^{12} is connected by a passageway t^3 . The passageways t^2, t^3 are made with necks t^4, t^5 , with which connect the ends of the pipe t, t' . The ports of the inlet valve chambers r^{11}, r^{12} , and of the exhaust valve chambers r^{15}, r^{16} are controlled by valves r^{18}, r^{19} , of the "puppet type," as shown in Fig. 7. These valves are made with stems $r^{20}, r^{21}, r^{22}, r^{23}$, as shown in Figs. 2, 3, 6 and 7; the valve stems r^{22}, r^{20} bearing on the outer of the cams r^6 , and the valve stems r^{21}, r^{23} bearing on the inner of said cams, and said valves are operated by the rocking of the cam shaft r^2 . The air inlet valves control the passage of air through the pipes t, t' , into the opposite ends of the pneumatic cylinder h . In this way, when the cam shaft r^2 is rocked the air will be admitted to one end of the pneumatic cylinder h and simultaneously discharged from the opposite end thereof. Since the air inlet and the exhaust valves are operated in unison with each other and by the same medium, air is simultaneously admitted and exhausted at the opposite ends of the pneumatic cylinder h proportionately, and in this way the piston k in the cylinder h is held under complete control.

The valve gear mechanism shown in Fig. 8, by which the engine control lever, e , is operated is of the well known "hunting type." This valve gear mechanism is operated by the valve mechanism r , which is connected to and controlled by the lever u' on the control stand u . The operation of said valve gear mechanism is illustrated in Fig. 8. The operating devices of the valve mechanism r are shown in Figs. 1, 2 and 8, in their normal state, which is when all the ports of said valve mechanism are closed by its valve. Let it then be assumed that the operating lever u' of the valve mechanism r has been operated to position the floating link r^9 , as shown in broken lines in Fig. 8. Since the lower end of the floating link is connected to the fulcrum pin y' on the link y , said movement of the link r^9 will throw the arm r^8 on the cam shaft r^4 to the left, with respect to Fig. 8, against one of the stops r^3 , thereby correspondingly opening the air inlet valves and exhaust valves of the valve mechanism r , controlling the pneumatic cylinder h and causing a relative movement of the piston k . The consequent movement of the link y will then cause the floating link r^9 to be rocked on the fulcrum pin 2 , connecting the link r^9 with the link r^{10} , and such action would cause the reverse movement of the arm r^8 of the cam shaft r^4 until the valve mechanism r is restored to its normal state, that is, again having all its valves closed, thereby holding the control

lever, *e*, in the position in which it has been placed by the prior operation of said valve mechanism *r*.

I claim:

- 5 1. The combination with a device controlled by a lever, of fluid actuated means for operating such lever substantially as described, comprising a cylinder a fluid actuated piston operating therein, said cylinder 10 being provided with inlet and outlet ports, valves controlling the ports, means for operating the valves, such means including a rockable arm, a floating link connected at one end to the extremity of such arm, 15 manually controlled operating means, connected to said floating link, a rod extending from the piston, the outer end of which rod is connected with said control lever of the device, such connection being adapted to 20 permit some movement in either direction without correspondingly moving said control lever, and a rod pivotally connecting the other end of said floating link with said piston rod.

2. The combination with a device controlled by a lever, of fluid actuated means for operating such lever substantially as described, comprising a cylinder a fluid actuated piston operating therein, said cylinder being pivotally supported at its sides, and 30 provided with inlet and outlet ports, valves controlling the ports, means for operating the valves, such means including a cam shaft, a rockable arm fixed thereon, a floating link connected at one end to the extremity of such arm, manually controlled operating means, connected to said floating link, a rod extending from the piston, the outer end of which rod is connected with 35 said control lever of the device, and a rod pivotally connecting the other end of said floating link with said piston rod. 40
